(57) **CLAIM**

The ornamental design for a combined flashlight with jump starter, as shown and described.

DESCRIPTION

FIG. 1 is a front perspective view of the combined flashlight with jump starter.

FIG. 2 is a back perspective view of the combined flashlight with jump starter.

FIG. 3 is a top view of the combined flashlight with jump starter.

FIG. 4 is a bottom view of the combined flashlight with jump starter.

FIG. 5 is a left side view of the combined flashlight with jump starter. The right side view is a mirror of the left side and therefore not shown.

FIG. 6 is a front view of the combined flashlight with jump starter; and,

FIG. 7 is a back view of the combined flashlight with jump starter.

The broken lines in the drawings depict portions of the combined flashlight with jump starter that form no part of the claimed design.
